REFRIGERATION

Curtis C. Coons, North Canton, Ohio, assignor to
 The Hoover Company, North Canton, Ohio, a
 corporation of Ohio

Application January 31, 1938, Serial No. 187,830

12 Claims. (Cl. 62—5)

This invention relates to refrigerating apparatus and more particularly to a means and method of regulating the flow of an inert gas through certain parts of a refrigerating system.

In three fluid absorption refrigerating systems as heretofore constructed, the inert gas has been circulated by gravity or by some power-driven means such as an electric motor-driven fan. These systems sometimes possessed the disadvantage that the rate of flow of the inert gas was not properly proportioned relative to the rate at which liquid refrigerant was supplied to the evaporator to produce refrigeration. As a result of this action, there would be insufficient inert gas circulating through the evaporator to produce refrigeration efficiently when the generator of the system was operating at maximum capacity. On the other hand, too much gas would be supplied to the evaporator to produce refrigeration efficiently when the generator was operating at low capacity.

Accordingly, it is an object of this invention to overcome the difficulties above enumerated by properly proportioning the rate of flow of the inert gas and the rate at which refrigerant is generated in the boiler. More specifically, I propose positively to circulate the inert gas by a mechanism having a constant gas circulating capacity and to regulate the actual rate of circulation of the gas by throttling the same in accordance with the rate at which heat is supplied to the refrigerant generator.

Other and further objects of the invention will become apparent as the description proceeds when taken in connection with the accompanying drawing, in which:

Fig. 1 is a diagrammatic representation of a refrigerating system embodying my invention;

Fig. 2 is a sectional detail view of a control mechanism drawn to an enlarged scale;

Fig. 3 is a view taken along the line 3—3 of Figure 2 and looking in the direction of the arrows; and

Fig. 4 is a sectional view taken along the line 4—4 of Figure 2 and looking in the direction of the arrows.

Referring now to the drawing in detail and first to Figure 1 thereof, it will be seen that I have illustrated diagrammatically, and by way of example only, a continuous three-fluid absorption refrigerating system comprising a boiler B, a condenser C, an evaporator E, an absorber A, and a circulating fan F driven by an electrical motor M. The refrigerating elements just described are suitably interconnected by various

conduits to form a plurality of gas and liquid circuits to constitute a complete refrigerating system.

The refrigerating system is suitably charged with a refrigerant such as ammonia, an absorbent such as water, and an inert pressure equalizing medium such as hydrogen or nitrogen.

Application of heat to the boiler B liberates refrigerant vapor from the refrigerant absorbent solution therein contained. The refrigerant vapor finds its way into a vapor lift pipe 11 and travels upwardly therethrough in the form of slugs spaced apart by slugs of weak absorption solution in the well known manner. The vapor and solution elevated through the conduit 11 discharge into a gas separation chamber 12 in which they separate and travel separately through their respective circuits. The weak solution is conveyed from the gas separation chamber 12 through a conduit 13, the liquid heat exchanger 14, and a conduit 15 into the upper end of the tubular inclined air-cooled absorber A. The weak solution flows downwardly through the air-cooled absorber A in counterflow relationship to a mixture of inert gas and refrigerant vapor flowing upwardly therethrough. The refrigerant vapor content of the mixture is absorbed by the absorption solution thereby strengthening its concentration. The strong solution is drained from the lower end of the absorber through a conduit 16, liquid heat exchanger 14, and a conduit 17 into the boiler B thus completing the solution circuit.

The refrigerant discharged into the separation chamber 12 is discharged therefrom through a conduit 21 into the upper portion of a tubular air-cooled condenser C. The conduit 21 includes an air-cooled rectifier R which condenses any vapor of absorption solution which may pass the separation chamber 12. The refrigerant vapor is liquefied in the condenser by heat exchange with ambient air and is discharged therefrom into the evaporator E through a conduit 22. The liquid flows downwardly through the evaporator in counterflow relationship to a propelled stream of pressure equalizing medium. The refrigerant liquid evaporates into the pressure equalizing medium to produce refrigeration.

The lean pressure equalizing medium formed in the absorber A is conveyed from the upper portion thereof into the suction inlet of the circulating fan F by a conduit 24. The lean inert gas is placed under pressure by the circulating fan F and is conveyed therefrom to the outer member of a gas heat exchanger 27 by a conduit 26. The inert gas leaves the outer pass of the

gas heat exchanger and enters the bottom portion of the evaporator E through which it travels upwardly in counterflow relationship to the liquid refrigerant as the refrigerant evaporates thereinto. The rich inert gas formed in the evaporator is returned from the upper end thereof into the inner pass of the gas heat exchanger 27, from which it is conveyed through a conduit 29 including a throttling device 30 to the bottom portion of the absorber A through which the gas flows upwardly in counterflow relationship to absorption solution as described previously.

A control mechanism which is responsive to evaporator temperature conditions is indicated generally at 23. This control mechanism controls the energization of the motor through the electrical conductors 25 and regulates the supply of fuel to a boiler heating gas burner 18 through a fuel supply conduit 19. Preferably the control mechanism modulates the gas flame in response to variations in refrigeration demand and energizes the circulating motor except under conditions of substantial shut-off of the refrigeration; that is, under conditions such that a mere igniting or pilot flame is carried on the gas burner 18. The control mechanism per se forms no part of this invention. A preferred form of control mechanism is disclosed in the copending application of Curtis C. Coons and William H. Kitto, Serial No. 160,274, filed August 21, 1937, now Patent No. 2,262,656, dated November 11, 1941.

It will be understood that the refrigerating system disclosed herein is illustrated and described diagrammatically by way of example only. The specific structure of the various elements of the system and the arrangement of the parts thereof are susceptible of wide variation without departing from the invention.

The throttling device 30 includes a cylindrical conduit section 32 which is adapted to be inserted between separated sections of the conduit 29 to form a complete conduit with such separated sections. The conduit 32 is surrounded by a securing sleeve 33 which is suitably secured as by welding to the separated sections of the conduit 29. A cylindrical thermostatic housing 35 projects laterally from the sleeve 33 and extends into the products of combustion discharge flue 20. The end of the sleeve 35 positioned within the conduit 20 is sealed by a suitable end plug 36 which is secured to the sleeve 35 as by welding. A helical bimetallic thermostat 38 is carried within the sleeve 35 and is provided with a laterally projecting end portion 39 which is anchored in any suitable manner in the end plug 36. The opposite end of the bimetallic thermostat 38 is provided with a laterally projecting segment 40 which projects into a slot formed in the end of an enlargement 42 of a shaft 43. The shaft 43 is suitably journaled in the walls of the conduit section 32. A butterfly valve plate 44 is rigidly secured to the shaft 43 and is adapted completely to close the conduit 29 when in the dotted line position shown in Figure 3. The enlargement 42 is provided with a laterally projecting pin 46 which is adapted to cooperate with a fixed pin 47 carried by the cylindrical element 32 and positioned to be engaged by the pin 46 when the butterfly valve plate 44 is in the full open position illustrated in full lines in Figure 3.

The bimetallic thermostat 38 is responsive to the temperature of the flue gases flowing through the conduit 20 and serves to regulate the rate of flow of the inert gas flowing through the inert

gas circuit in accordance with the temperature of such gases.

The circulating motor M is preferably of the induction type in which a squirrel cage rotor is housed within a sealing shell and the field windings are placed without the shell. Such a motor operates at substantially constant speed wherefor the rate of inert gas circulation would be constant at all times were it not for the throttling device 30. The control mechanism will regulate the flame on the burner and thereby the rate at which refrigerant is generated in accordance with demand for refrigeration. The control mechanism increases or decreases the flame on the burner in response to demands for refrigeration. This correspondingly increases or decreases the rate at which refrigerant vapor is generated and at which refrigerant liquid is supplied to the evaporator E. In order that the rate of circulation of the inert gas may properly be proportioned with respect to the rate at which refrigerant liquid is supplied to the evaporator, the throttling mechanism 30 is provided. This mechanism is responsive to flue gas temperatures which are in turn a function of the rate at which heat is supplied to the boiler and at which refrigerant vapor is generated. The net result of this mechanism is that the thermostat operates to open the butterfly valve plate 44 to full open position when the control mechanism has turned the gas flame up to its maximum value. The gas conduit 29 will not be entirely blocked except during periods of complete inactivity of the refrigerating system. The pilot flame normally provided to ignite the main burner will supply sufficient products of combustion to keep the valve plate 44 slightly open.

From the description above it will be apparent that I have devised a refrigerating system in which the inert gas is positively circulated and in which the rate of flow of the inert gas is maintained in proper relationship to the rate at which liquid refrigerant is supplied to the evaporator. Obviously, the thermostatic mechanism 30 could be made responsive to conditions other than the flue gas temperature, for example, the temperature of the condenser or absorber.

The present invention provides a mechanism whereby the refrigerant concentration in the inert gas and absorption solution is maintained at its optimum value under all conditions of operation. If the concentration of the refrigerant in the rich inert gas is allowed to drop as is the case when only a small quantity of refrigerant is supplied to the evaporator and the rate of inert gas circulation is constant, the absorbing process will proceed inefficiently. On the other hand, if the refrigerant concentration in the inert gas is allowed to get too high the evaporating process proceeds in an unsatisfactory manner.

In the present invention the rate of absorption solution circulation is properly proportioned to the refrigeration demand and rate of refrigerant generation by the vapor lift circulating pump. The rate of inert gas circulation is geared to the refrigerating demand and rate of refrigerant generation under all variations of the load by the throttling valve in the inert gas circuit. Thus, the refrigerant concentration in any selected portion of the inert gas circuit is maintained at an optimum value at all refrigerating loads. Consequently, the apparatus may be designed for operation at a selected level of re-

frigerant concentration at various points and the mechanism of the present invention will substantially maintain these concentrations at widely varying rates of refrigeration production.

Since the rate at which the absorption solution is circulated between the boiler and the absorber is a function of the rate at which heat is supplied to the boiler, it follows that the rates of heat supply, inert gas circulation, absorption solution circulation, and production of refrigeration are all proportioned one to another and are regulated by the demand for refrigeration.

While I have illustrated and described a single embodiment of my invention, it is to be understood that the invention is not limited thereto but may be embodied in numerous other constructional forms and variations without departing from the spirit of the invention or the scope of the appended claims.

I claim:

1. That improvement in the art of refrigeration which includes the steps of expelling refrigerant vapor from solution by application of heat thereto, liquefying the vapor so expelled, evaporating the liquefied refrigerant into a propelled stream of an inert gas, applying a substantially constant propelling force to the inert gas and regulating the rate of flow of the inert gas in accordance with the rate at which heat is supplied to generate refrigerant vapor.

2. That improvement in the art of refrigeration which includes the steps of subjecting a solution of refrigerant in an absorbent to the action of a flame, liquefying refrigerant vapor liberated by the action of the flame, evaporating the refrigerant liquid so generated into a propelled stream of inert gas, and throttling the flow of the inert gas directly with variations in the temperature of the products of combustion of the flame.

3. Refrigerating apparatus comprising a boiler, a condenser, an evaporator, an absorber, means forming an inert gas circuit including said evaporator and said absorber, means forming a solution circuit including said boiler and said absorber, electrical power-driven means for circulating an inert gas through said inert gas circuit, and means operative automatically properly to proportion the rate of flow of inert gas to said evaporator and the rate at which liquid refrigerant is supplied thereto under varying refrigerating loads.

4. Absorption refrigerating apparatus including a boiler, a gas burner for heating said boiler, a flue for conveying waste products of combustion from said boiler, means forming a solution circuit including an absorber and said boiler, means forming a pressure equalizing medium circuit including said absorber and an evaporator, power-driven means for circulating an inert gas through said pressure equalizing medium circuit, a valve in said pressure equalizing medium circuit, and thermostatic means responsive to the temperature of the waste gases in said flue operative to regulate the setting of said valve.

5. Absorption refrigerating apparatus comprising a pressure equalizing medium circuit including an evaporator and an absorber, power-driven means for circulating a pressure equalizing medium through said circuit, a boiler for generating refrigerant vapor, means for supplying refrigerant vapor so generated to said evaporator in liquid form, control means responsive to the demand for refrigeration adapted to control the energization of said power driven means and the rate at which heat is supplied to said

boiler, and means for regulating the resistance of said inert gas circuit in accordance with the rate at which heat is supplied to said boiler.

6. Absorption refrigerating apparatus comprising a pressure equalizing medium circuit including an evaporator and an absorber, a boiler, means for supplying refrigerant generated in said boiler to said evaporator in liquid phase, power driven means for applying a substantially constant circulating force to the pressure equalizing medium to propel the same through said pressure equalizing medium circuit, and means for regulating the flow of said pressure equalizing medium through said circuit.

7. Absorption refrigerating apparatus comprising a pressure equalizing medium circuit including an evaporator and an absorber, a boiler, means for supplying refrigerant generated in said boiler to said evaporator in liquid phase, power driven means for circulating pressure equalizing medium through said pressure equalizing medium circuit, and means for regulating the flow of said pressure equalizing medium through said circuit, said regulating means including a throttling device and a thermostatic regulator therefor.

8. Absorption refrigerating apparatus comprising a pressure equalizing medium circuit including an evaporator and an absorber, a boiler, means for supplying refrigerant generated in said boiler to said evaporator in liquid phase, power driven means for applying a substantially constant circulating force to the pressure equalizing medium to propel the same through said pressure equalizing medium circuit, and a burner for heating said boiler, and means responsive to the temperature of waste products from said burner for regulating the flow of said pressure equalizing medium.

9. Absorption refrigerating apparatus comprising a pressure equalizing medium circuit including an evaporator and an absorber, a boiler, means for supplying refrigerant generated in said boiler to said evaporator in liquid phase, power driven means for circulating pressure equalizing medium through said pressure equalizing medium circuit, and a burner for heating said boiler, and means responsive to the temperature of waste products from said burner for regulating the flow of said pressure equalizing medium, said regulating means including a throttling device, a products of combustion flue for said burner, and a thermostat mounted in heat exchange relation with products flowing through said flue, said thermostat being operatively connected to said throttling device.

10. Absorption refrigerating apparatus comprising a pressure equalizing medium circuit including an evaporator and an absorber, a boiler, means for supplying refrigerant generated in said boiler to said evaporator in liquid phase, and means for regulating the flow of said pressure equalizing medium through said circuit, said regulating means including a throttling device, a products of combustion flue for said burner, and a thermostat mounted in heat exchange relation with products flowing through said flue, said thermostat being operatively connected to said throttling device.

11. Absorption refrigerating apparatus comprising an inert gas circuit including an absorber and an evaporator, a solution circuit including a boiler and said absorber, a constant speed circulator for propelling gases through said inert gas circuit, means for heating said boiler, and

means for regulating the rate of flow of said gases in accord with the rate of heat supply to said boiler.

12. Absorption refrigerating apparatus comprising an inert gas circuit including an absorber and an evaporator, a solution circuit including a boiler and said absorber, a constant speed circulator for propelling gases through said inert

gas circuit, means for heating said boiler, means for regulating the rate of flow of said gases in accord with the rate of heat supply to said boiler and control means responsive to the demand for refrigeration for regulating the rate of heat supply to said boiler and for controlling the operation of said circulator.

CURTIS C. COONS.
